A LINK CHAIN FOR A BRACELET

Jerome A. Gonicberg, Providence, R.I.

Application May 19, 1958, Serial No. 50,964

Term of patent 3½ years

(Cl. D45—4)

F I G. 1

F I G. 2

F I G. 3

Fig. 1 is a plan view of a link chain for a bracelet, showing my new design.

Figure 2 is a side elevational view, and

Figure 3 is an enlarged perspective view of the second and third links from the left in Fig. 1.

The dominant features of my design reside in the portion shown in full lines.

I claim:

The ornamental design for a link chain for a bracelet, as shown and described.
